BLOCK-DIVIDING RECIPROCATING-SAW
WOODWORKING MACHINELaurence E. Topham, Wenham, Mass., assignor
to United Shoe Machinery Corporation, Flem-
ington, N. J., a corporation of New Jersey

Application February 9, 1944, Serial No. 521,679

9 Claims. (Cl. 143—75)

1

This invention relates to woodworking machines and is particularly concerned with machines for dividing a block of wood or similar material by a sawing operation.

In the manufacture of shoe lasts comprising separate, pivotally joined foreparts and rearparts, it is customary to process the foreparts on a last lathe by a turning operation performed on wood blocks having roughly a cylindrical shape, one such block furnishing one last forepart. In finish-turning last foreparts on a last lathe it is necessary, due to the considerable difference in shape between the finished last forepart and the rough block from which it is produced, to remove a substantial amount of waste material from the block during the turning operation, making that operation both costly and time consuming.

Sometimes the rough wood block is trimmed prior to the finish-turning to remove some of the bulk of the waste or excess material normally produced in the finish-turning of a last forepart. This is done by manually presenting the block to a circular saw, an operation which requires high skill and considerable judgment in preventing the circular saw from cutting off too much material. Moreover, this operation is extremely dangerous and has resulted in many accidents. This becomes particularly apparent when realizing that the pieces of material to be trimmed off are irregular in size and shape, a fact which necessitates manual rotation and other manipulation of the block while being operated upon by the circular saw. Even though this procedure may speed up the finish-turning process, it does by no means avoid the loss and waste of a substantial amount of excess wood.

It is therefore an object of the present invention to mitigate the removal from forepart blocks of a large amount of excess material as waste in the finish-turning of last foreparts by the last lathe.

To this end the invention, in its method aspect, provides dividing a last forepart block of conventional size or of only slightly larger than conventional size into two nested components by a helical cut extending from one end face of the block to the other, and finish-turning each component in a last lathe to produce a last forepart. Thus one last forepart block furnishes two last foreparts.

To divide the last forepart block there is provided, in accordance with another feature of the invention, a machine having a saw, a support for the last forepart block, and mechanism for simul-

2

taneously rotating and longitudinally moving the support with a block mounted therein so as to feed and rotate the block past the saw and to divide the block into two nested components by a helical cut.

In accordance with a further feature of the invention, the rotary and longitudinal movements of the block support are obtained by two axially aligned screw shafts which are rigid with the support, an axially immovable, positively rotated nut engaging one of these shafts to rotate the entire assemblage comprising the block support and the two shafts, and a stationary nut engaging the other shaft to control the extent of rotation and longitudinal movement of the assemblage.

In accordance with another feature of the invention, the support for the block is actuated to perform a work feeding operation in time relation with the operation of the saw, and in particular the feed motion of the support is retarded or even reduced to zero during the upstroke of the vertically reciprocating saw so as to prevent a binding of the saw in its kerf.

Still another feature of the invention is the provision of mechanism for initially positioning the block in the block support with relation to the saw, prior to the initiation of a sawing operation. After the positioning of the block and immediately prior to the initiation of a sawing operation, the block positioning mechanism and block support are locked together to move as a unit.

A further important feature of the invention consists in the provision of a saw having its blade twisted along its longitudinal axis, and a support for the saw provided with a threaded member having a helix angle substantially equal to the helix angle of the twisted saw blade, the threaded member cooperating with a stationary member to rotate the saw support during the reciprocation thereof. Thus the helically twisted saw moves like a screw through the work, which in this instance is the equivalent of a fixed nut.

These and other features of the invention are hereinafter described more specifically in connection with the accompanying drawings, and are pointed out in the claims.

In the drawings:

The illustrated machine serves the purpose of dividing wood block having a roughly cylindrical shape, such as are commonly used in the manufacture of last foreparts, into two nested components. The division is made by a helical cut such that the dividing faces of the two components of a block constitute each a hyperbolic paraboloid complementary to the other. As a result, two last foreparts may be manufactured from a block of the same size as, or only slightly larger than, a block from which heretofore only one last forepart was produced. To secure this result there is provided a sawing mechanism generally indicated at 10 in Figs. 1 and 6, and a work support, or more specifically, a last forepart block support generally indicated at 12 in Figs. 1 and 15. The block support 12 is constructed and arranged to rotate about its longitudinal axis and to move longitudinally along this axis so as to feed a roughly cylindrical wood block B maintained in the support 12, past the saw and simultaneously to rotate the block B so as to saw the block into two nested parts or components

B' and B² divided along a helical cut as illustrated in Fig. 19. Each block part or component B' or B², as shown in Figs. 20 and 21, is roughly in the shape of a last forepart L (Fig. 22) and requires the removal of only a relatively small amount of excess or waste material in its finish-turning. The sectional views of Figs. 23 to 25 show the closeness in size and shape of the block component and the finished last forepart.

The following detail description of the construction and operation of the illustrated machine is divided into descriptions of the main groups of elements of the machine, including the main driving mechanism, the sawing mechanism and the work supporting and feeding mechanism.

The machine frame comprises a substantially box shaped base 14 (Figs. 1 and 6) to the upper portion of which are bolted at opposite sides thereof two laterally and upwardly extending arms 16 and 18. The upper ends of the arms 16 and 18 serve to support mechanism, to be described, for actuating the work support 12 or for controlling the actuation thereof.

The main drive.—As illustrated in Fig. 1 the base 14, has a left hand extension 20 serving as a bracket or support for a motor 22. A small pulley 24 (Fig. 6) on the rotor shaft of the motor 22 is in driving connection by a belt 26 with a pulley 28 secured on a shaft 30 arranged in suitable bearings in the machine frame, and hereinafter referred to as the main shaft. The main shaft 30 serves to actuate the sawing mechanism 10 and the work support 12. To actuate the sawing mechanism, the main shaft 30 has splined to its forward end a disk 32 (Figs. 1, 2 and 6) which is provided near its circumference with a crank pin 34. The connections between the crank pin 34 and the sawing mechanism will be presently described. To actuate the work support, the main shaft 30 has secured to its rearward portion a small pulley 40 (Fig. 6) which is connected by a belt 42 to a pulley 44 of the same size as the pulley 40. The pulley 44 is secured on the rear portion of a counter shaft 46 (Figs. 6 and 7) which is rotatably mounted in fixed bearings in the machine frame and on which is secured a pinion 48 meshing with a pinion 50 on a cam shaft 52 serving to actuate the work support. The cam shaft 52 is maintained for rotation and axial movement in suitable bearings provided in the machine frame. The pinions 48 and 50 are of sufficient width to maintain driving connection between them in spite of axial movements of the cam shaft 52. The connections between the cam shaft 52 and the work support 12 will be described further below.

The sawing mechanism and its actuation.—The saw comprises a blade 60 (Figs. 1 and 6) which is twisted about its longitudinal axis so that the opposite ends of the saw blade are disposed with relation to each other at an angle of about 90°. The saw blade 60 is maintained, as will be more specifically described, in a support 62 comprising substantially two looped members which are joined at their upper and lower ends and which are curved laterally and forwardly, or rearwardly respectively, so as to avoid interference with the work support as the latter is caused to move the work contained therein past the saw. The lower end of the saw support 62 is secured to the upper end of a multiple helically splined shaft or multiple threaded screw 64 extending vertically through a stationary nut 66 having a flange at its upper end and being supported in a portion of the machine frame. In setting up or as-

sembling the machine parts, the nut 66 may be adjusted by a limited rotation about its vertical axis, whereupon the nut is secured in adjusted position by clamping screws 68 (Fig. 1) extending through curved slots in the flange of the nut and threaded into the machine frame. The splined shaft 64 has a lower continuation in the form of a rod 70 having a smooth surface and maintained for sliding movement in and with relation to a fixed bearing 72. Upon vertical reciprocation of the splined shaft 64 and the saw support 62 by the crank pin 34, as will be described, the saw support 62 is given a rotary motion as a result of the movement of the splined shaft 64 through the stationary nut 66. The helix angle of the threads of the shaft 64 is substantially the same as the helix angle of the helically twisted saw blade 60. Consequently, the saw in moving through the kerf in the work, is moved in the direction of its longitudinal axis as well as rotated about this axis so that its motion through the work may be compared with the motion of the shaft 64 through the fixed nut 66, the work in this case corresponding to the latter.

The crank pin 34 acts upon the sawing mechanism by means of a connecting rod 74, the upper end of which is connected to the splined shaft 64 for universal movement relatively thereto. For this purpose, the lower end of the splined shaft 64 has secured to it a collar 76 (Figs. 1, 2 and 6) provided with a laterally and forwardly extending arm 78, integral with which is a depending pin 80 (Fig. 2). The pin 80 is pivotally received in a sleeve or bearing member 82 surrounding a horizontal pin 84 and secured thereto by a set screw (not shown). The pin 80 extends through the bearing member 82 and is held therein by a nut 85 threaded upon the lower end of the pin 80 and bearing against the bearing member 82. Rotatably mounted on the horizontal pin 84 is a cross shaped hollow block 86 in which the bearing member 82 is contained for movement relatively thereto and which in turn is pivotally secured by trunnion pins (not shown) to a yoke 88 (Fig. 1), provided at the upper end of the connecting rod 74. The lower end of the connecting rod 74 cooperates with the above-mentioned crank pin 34 in the following manner. The lower end of the connecting rod 74 has a U-shaped or yoke shaped portion 90 upon which fits a complementary member 92 secured thereto by screws 94 to hold in place two block shaped members 96 (Fig. 2) which are machined out to provide a spherical socket for the ball shaped head 98 of the crank pin 34.

As will be noted, upon rotation of the shaft 30, which is uniform, and the disk 32 as well as the crank pin 34, the saw support 62 and the saw blade 60 secured therein, are reciprocated vertically, and at the same time, by reason of the engagement of the splined shaft 64 with the stationary nut 66 and the vertical movement of the shaft through the nut, the shaft 64 and the saw frame 62 supported by it, are rotated about the longitudinal axis of the saw blade, which coincides with the longitudinal axis of the splined shaft 64.

The upper end of the saw blade 60 is secured in the saw support 62 in the following manner: As illustrated best in Fig. 3, the saw support 62 has a boss-like upper end, in which is mounted a saw receiving block 100. The block 100 is adjustable vertically to adjust the tension of the saw blade, and to this end the block is provided with an upwardly extending threaded stem 102,

engaged by a nut 104 and a check nut 106, the nut 104 resting against a washer 108, seated upon the upper end of the saw support 62. To receive the saw blade, the block 100 is provided with a vertically extending slot 110. Integral with the lower end of the block 100 is a rectangular block 112 through which the saw receiving slot 110 extends and which is provided with horizontally coaxial bore holes. The saw blade is provided with a similar hole which is moved into alignment with the bore holes so that a saw securing pin 114 may be driven through the block 112 and the saw received therein. To prevent rotation of the block 100 and the parts connected therewith with relation to the saw support 62 upon vertical adjustment of the block, there is provided a pin and slot connection 116 between the block 100 and the upper end of the saw support 62.

The lower end of the saw is secured in the saw support 62 in the following manner: The aforementioned splined shaft 64 has a reduced upper portion 117 (Fig. 4) provided with a central bore hole of substantial diameter. The upper portion 117 of the splined shaft 64 fits into a central socket provided at the lower end of the saw support 62 and extends therethrough. In the assembled condition of the machine parts there is contained in the bore of the upper portion 117 a cylindrical block 118 provided with an inclined saw receiving slot 120, the inclination of the slot corresponding in its angularity to the helix angle of the twisted saw blade 60. The lower end of the saw blade extending into the slot 120, is secured in the block 118 by a horizontal pin 122, driven through aligned bore holes of the block 118 and a corresponding hole in the saw blade aligned therewith. Mounted on top of the cylindrical block 118 is a disk 124 having certain portions along its periphery machined out to provide lands 126 engaging a groove 128 provided near the upper end of the bore in the portion 117 of the shaft 64. The overhanging flange 129 produced by the groove 128 also is machined out along certain portions of its perimeter to produce lands 130 (Fig. 5). Upon assemblage of the machine parts, the disk 124 is brought into engagement with the slot 120 (after the block 118 with a saw blade received therein has been placed into the bore of the portion 117) by passing its lands 126 through the machined out portions of the flange 129, whereupon by rotation of the disk 124, it may be held against vertical displacement in the fashion of a bayonet lock. The disk 124 also has a saw receiving slot which is a continuation of the slot 120. Thereafter, the disk 124 and the block 118 are secured together by screws 132 (Fig. 5).

To twist the saw blade 60 and maintain it in a twisted condition, the disk 124 has pivotally secured to it a dog 134, one end portion of which may be brought to engage an end face on one of the lands 130 to hold the disk 124 and block 118 against the tendency of the saw blade to untwist or rotate back into straight position. The dog 134 is preferably so positioned with relation to the shaft 64 that the opposite ends of the saw blade are disposed at an angle of 90° relatively to each other.

In order to prevent the saw support 62 from rotating with relation to the upper end of the splined shaft 64, the two are connected by a key 138 (Fig. 4), held in the lower end of the saw support 62 and extending into a vertical keyway 136, provided in the upper portion 117 of the shaft 64. This entire assemblage, partic-

ularly shaft 64 and saw support 62, is held together by a nut 140 threaded upon the portion 117 projecting out of the socket of the saw support 62; the nut 140 being tightened against the upper end of that socket.

The work supporting and feeding mechanism and its actuation.—The work support 12 comprises principally a hollow shell-like member 200 (Figs. 1 and 15) which is substantially cylindrical and has openings cut out along helically extending edges 202, and slots 204 also extending helically in the direction of the axis of rotation of the work support to provide clearance for the saw blade 60, cooperating with the work support and passing through it. The shell-like member 200 connects two axially aligned, helically splined shafts or screw shafts 206 and 208 having multiple threads with which the shell-like member 200 is integral. The shafts 206 and 208 support the shell-like member 200 and actuate it so as to feed and turn the work.

The right-hand shaft 208 is supported in the upper end of the previously mentioned arm 18 of the machine frame. To this end the upper extremity of the arm 18 is formed as a two part clamp 210 in which is received a nut 212 (Fig. 13). The nut 212 is in threaded engagement with the screw shaft 208 and is held against rotation by the action of the clamp 210. To prevent axial movement of the nut 212 it is provided at its opposite ends with flanges 214 and 216, abutting the end faces of the clamp 210. The two parts of the clamp 210 are held together in firm clamping engagement by screws 218. As illustrated best in Fig. 14, the nut 212 is provided with an adjustment to facilitate its assemblage in the setting up of the machine parts. The lower portion of the flange 216 of the nut 212 has in it an arcuate slot 222 through which extends a clamping screw 220 threaded into the lower portion of the clamp 210. With the clamping screw 220 backed off, the nut 212 may be rotated to the extent permitted by the length of the slot 222. Thereafter, the clamping screw 220 is tightened to connect together the nut 212 and the clamp 210.

The left-hand shaft 206 is supported in the upper end of the previously mentioned arm 16 of the machine frame in a manner similar to that just described in connection with the right-hand shaft 208. The upper end of the arm 16 also is formed as a two part clamp 226 (Figs. 1 and 10), the two parts of which are held together by screws 228 and afford a bearing for a nut 230. The nut 230 is in threaded engagement with the screw shaft 206 and is rotatably supported in the clamp bearing 226. The nut 230 is axially immovable and for this purpose it is provided at its right-hand end with a collar 234 splined to the nut 230 and abutting one end face of the clamp 226. At its left-hand end the nut 230 has a flange 236 which contacts the other end face of the clamp 226 and is in the form of a gear. By the rotation of the gear 236, the nut 230 is rotated to rotate the screw shaft 206 and the mechanism connected therewith, as will be described presently.

As will be seen from the above description of the construction of the work supporting and feeding mechanism, the screw shaft 206 is rotated by the gear 236 which is integral with the nut 230. Since the shell 200 and the screw shaft 208 are integral with the screw shaft 206, they are rotated with the latter. However, the screw shaft 206 and the nut 230 do not rotate solidly

together, there being a differential rotation and an endwise movement of the screw shaft 206 with relation to and through the axially immovable nut 230. The endwise or axial movement of the screw shaft 206 and hence of the shell 200 and the screw shaft 208 is the result of the rotation of the screw shaft 208 through the stationary nut 212. It is understood that the screw shaft 208 by reason of its rotation with relation to the stationary nut 212 is constrained to move endwise or longitudinally in the direction of its axis of rotation. In view of the fact that the nut 212 is stationary and has a predetermined helix angle, the extent of the longitudinal movement of the screw shaft 208 and hence the extent of longitudinal movement of the shell 200 and the screw shaft 206 is determined by the stationary nut 212. At the same time it is to be noted that the extent of rotary motion imparted to the screw shaft 208, the shell 200 and the screw shaft 206 during a predetermined endwise movement and sufficient to move the work past the saw, is also determined by the stationary nut 212. As a matter of fact, during the predetermined endwise movement of the work supporting mechanism it is constrained by the nut 212 to make approximately one-half of a revolution.

In the illustrated embodiment of the invention, the arrangement is such that the helix angle of the screw shaft 206 differs from the helix angle of the screw shaft 208. In the particular instance, the helix angles of the shafts 206 and 208 are so selected that the shaft 208 has the smaller helix angle. The purpose of this arrangement is to cause the screw shaft 206 in cooperating with the rotary nut 230 to tend, so to speak, to feed ahead, thus preventing any backlash of the screw shaft 208 with relation to the stationary nut 212.

40. The compound rotary and longitudinal motion of the shell 200 causes the work supported therein to be fed past the saw and simultaneously to be turned or rotated so that a helical cut is made by the saw 60 through the work from one end face thereof to the other.

45. Prior to the initiation of a sawing operation, the wood block B supported in the shell 200 is located with relation to the saw 60. This relation is best illustrated in Fig. 15. One end face of the wood block is positioned opposite the toothed edge of the saw, the latter passing through the slot 204 of the shell 200. During one sawing operation, the entire length of the block B is fed past the saw.

50. 55. As illustrated in Fig. 1, the screw shafts 206 and 208 have oppositely extending threads. The reason for this will become apparent upon the following consideration. In order to bring about a feed movement of the work supporting shell 200 from the position illustrated in Fig. 1 toward the left, it is necessary, since the gear 236 is rotated in a clockwise direction as viewed from the left-hand side of the machine, that the screw shaft 206 has right-hand threads. The nut 212 60. 65. cooperating with the screw shaft 208 being stationary, it is necessary that the shaft 208 has left-hand threads in order to be rotated in the same direction as the shaft 206.

70. After the completion of one feed movement of the work supporting shell 200 past the saw 60, it is automatically brought to a stop as will be explained, whereupon the shell 200 and both screw shafts 206 and 208 are manually returned to initial position. As indicated in Fig. 13, the 75 screw shaft 208 is hollow and its right-hand end

is closed by a fitting 240 which is in threaded engagement with internal threads in the said end of the shaft 208. Threaded into tapped bores of the fitting 240 and extending at right angles to the longitudinal axis of the shaft 208 are two handles 242, this mechanism constituting a capstan by which the shaft 208 and with it the shell 200 and the shaft 206 may be returned to initial position by a combined longitudinal and rotary motion.

The mechanism for initially positioning the work.—Before the initiation of a sawing operation, the block B is positioned in the shell 200 so as to locate it initially in a predetermined position with relation to the saw 60, the mechanism accomplishing this also serving to secure the block in the shell 200 in this predetermined position. To this end, there are provided two pairs of block engaging prongs 250 and 252 which are movable in opposite directions toward and from each other parallel to the axis of rotation of the shell 200. The two prongs of each pair extend horizontally and their horizontal alignment is maintained during the positioning of the work. The left-hand prongs 250 are illustrated in Figs. 10, 11 and 15, and the right-hand prongs 252 are illustrated in Figs. 13 and 15. The mounting of the left-hand prongs 250 is as follows:

Referring to Fig. 10 it will be noted that the screw shaft 206 also is hollow and its left-hand end is closed by a fitting 254 threaded into it. Rotatably mounted in a bore extending through the fitting 254 is the reduced left-hand end 256 of a rod 258 extending along the interior of the screw shaft 206. At its left-hand extremity the reduced end 256 has secured to it a hand wheel 260 by which it may be rotated. The rod 258 is immovable axially in both directions. To this end, the hub 262 of the hand wheel 260 is arranged to abut the left-hand end face of the fitting 254. This prevents movement of the rod 258 toward the right of Fig. 10. Axial movement of the rod 258 in the opposite direction is prevented by the engagement of a shoulder on the rod 258 with the right-hand end face of the fitting 254. A right-hand portion 266 of the rod 258 also is reduced in diameter. The portion 266 is threaded and is in engagement with an internally threaded tube 268, also extending along the interior of the hollow screw shaft 206. The tube 268 is slidably maintained inside the shaft 206. As will be noted, upon rotation of the hand wheel 260 the rod 258 is rotated but prevented from axial movement and the rotary motion of the threaded right-hand portion 266 of the rod 258 causes an axial movement of the tube 268 in one direction or the other depending upon the direction of rotation of the hand wheel 260. The tube 268 serves to support the prongs 250. For this purpose, the tube 268 is provided with a forked front end 272 (Figs. 10 and 11) and a pin 274 extends crosswise through the fork at right angles to the longitudinal axis of the tube 268. Secured on the pin 274 is a casing 276 housing the end 272 and the mechanism connected therewith (Fig. 11). Mounted in the casing for sliding movement parallel to the axis of the tube 268 and the screw shaft 206 are two blocks 278 located diametrically opposite to each other. The blocks 278 are cylindrical and provided with apertures in their front ends in which are received and secured by set screws 280 the two prongs 250. The set screws 280 extend through slots 282 provided in the walls of the casing 276 to prevent the blocks 278 from rotating

about their longitudinal axes. The rear end faces of the blocks 278 are in engagement with an equalizer 284 rotatably mounted on the pin 274. Thus the two prongs 250 may move independently of each other to a limited extent in the axial direction of the screw shaft 206, so as to accommodate uneven end faces of the block B to be clamped in the shell 200. Undue movement of the equalizer 284 is prevented by a conical stop face 286 provided at the forked end 272 of the tube 268 and cooperating with the rear face of the equalizer 284.

To keep the prongs 250 in horizontal alignment during their movement caused by the rotation of the hand wheel 260, the tube 268 is provided with a slot 290 (Fig. 10) engaged by a pilot screw 292 mounted in the hub of the shell 200. Thus the tube 268 is prevented from undue rotation so as to prevent the prongs 250 from fouling the saw 60. After the prongs 250 have been advanced with relation to the screw shaft 206 and the shell 200 to position and secure the block B in the shell 200, the tube 268 carrying the prongs 250 is prevented from further movement with relation to the screw shaft 206 by the tightening of a binding stem 294, locking the tube 268 to the screw 206 so that henceforth both move as a unit during the ensuing sawing operation. Thus the predetermined position of the work with relation to the shell 200 is maintained. The binding stem 294 is operated by a handle 296 (Fig. 15), which is in engagement with the threaded upper end of the stem 294.

The right-hand prongs 252 (Fig. 13) are mounted in the machine in a manner similar to that of the left-hand prongs 250 described above. The hollow screw shaft 208 is closed at its right-hand side by the previously mentioned fitting 240. A rod 300 extends along the interior of the screw shaft 208 and has a reduced right-hand portion 302 extending through the fitting 240 and rotatably mounted therein. The portion 302 carries at its right-hand extremity a hand wheel 304 by means of which the rod 300 may be rotated. The rod 300 is immovable axially. To this end, the hub 306 of the hand wheel 304 is arranged to abut the fitting 240. This prevents axial movement of the rod 300 toward the left of Fig. 13. To prevent axial movement of the rod 300 toward the right of Fig. 13 a shoulder formed by the reduced right-hand portion 302 abuts against the left-hand end face of the fitting 240. The rod 300 also has a reduced left-hand portion 308 which is threaded and is in engagement with the internal threads of a tube 310. The tube 310 is movable in the direction of its longitudinal axis upon rotation of the rod 300 by the hand wheel 304. The tube 310 is received in a bearing sleeve 312 mounted in the interior of the screw shaft 208 and held in place therein. At its left-hand end the tube 310 carries an equalizing mechanism for the prongs 252, which mechanism is identical in construction and purpose with the equalizing mechanism of the prongs 250. To prevent rotation of the tube 310 on rotation of the rod 300 and thus limit the motion of the tube 310 substantially to a longitudinal motion for the purpose of keeping the prongs 252 in horizontal alignment, the tube 310 is provided with a slot 314 extending lengthwise thereof and engaged by a pilot screw 316 threaded through the right-hand hub of the shell 200. As will be seen, upon rotation of the hand wheel 304 the tube 310 carrying the prongs 252 is advanced or retracted depending upon the direction of rotation of the hand

11

wheel 304. This movement of the tube 310 and the prongs 252 is with relation to the shaft 208 and the work-supporting shell 200 integral therewith. After this work-engaging and work-positioning movement of the prongs 252 has been terminated the tube 310 is locked to the shaft 208 by the tightening of a binding stem 318 provided with an operating handle 320 (Fig. 15).

In clamping a wood block B in the machine and locating it in a predetermined position with relation to the saw 60, the block B will be inserted into the shell 200 which, at that time, is in its initial position (Fig. 1), that is, the position from which it begins its work-feeding motion. Upon rotation of the hand wheels 260 and 304 both pairs of prongs 250 and 252 are advanced toward the block, while maintaining their horizontal alignment, so as to engage the end faces of the block and impale the latter, thus holding the block within the shell 200. It is to be understood that any irregularities in the end faces of the block engaged by the prongs 250 and 252 are automatically accommodated by the self-adjusting prongs. The final position of the block B with relation to the shell 200 is maintained and secured by the operation of the handles 296 and 320 taking up on the binding stems 294 and 318 so as to lock the prongs and the mechanisms carrying and moving them to their respective screw shafts 206 and 208.

It has been stated that the work support is driven by the positively rotated gear 236 which is integral with the nut 230, the latter being in threaded engagement with the screw shaft 206. Moreover, it has been pointed out that the previously described shaft 52 (Figs. 6 and 7) serves to actuate the work support. The connections, including a clutch mechanism between the shaft 52 and the gear 236, are as follows: As illustrated best in Fig. 7, a worm 330 is secured on the left-hand portion of the shaft 52 and is in driving engagement with a worm gear 332. The worm gear 332, as illustrated best in Fig. 1, is part of a speed-reducing mechanism generally indicated at 334 and containing a series of stub shafts and intermeshing gears, including a gear 336 which meshes with a gear 338 on a clutch shaft 340 (Fig. 8). The clutch shaft 340 is rotatably mounted in a bracket which is part of the left-hand arm 16 of the machine frame and carries a gear 342 loosely rotatable thereon but axially immovable relatively thereto. Integral with the gear 342 is a frustoconical friction clutch member 344 which is the driven member of a clutch. The driving member of the clutch is identified at 346 and is fast on the shaft 340 in the sense that it is constrained to rotate therewith but may be displaced axially with relation thereto so as to move into and out of driving engagement with the member 344. A spring 350 interposed between a collar 352 fixed on the left-hand extremity of the shaft 340 and the hub 354 of the driving clutch member 346 tends to slide the member 346, which is continuously rotated as a result of the continuous rotation of the shaft 340, to the right of Fig. 8 to engage the clutch member 344 and rotate the gear 342 which meshes with the gear 236, thereby rotating the nut 230, with the results previously explained. The hub 354 of the clutch member 346 has a circumferential groove which is engaged by the forked end of a clutch-shifting lever 356 pivotally secured at 358 to a bracket arm 360 which is part of the machine frame. Substantially midway between its ends the lever 356 is pivotally engaged by one end of a toggle com-

12

prising two links 362 and 364 connected together by a center joint 366. The toggle link 364 is pivotally secured at 370 to the machine frame and has integral therewith and extending at right angles thereto a handle 368. Movement of the handle to the right of Fig. 8 breaks the toggle and permits the spring 350 to establish driving connection between the clutch members 344 and 346 so that the work-supporting assemblage will be actuated.

As has been previously explained, during the actuation of the work-supporting assemblage it is moved from the position illustrated in Fig. 1 toward the left. This motion is utilized automatically to throw out the clutch 344, 346 on termination of a sawing operation. To this end the handle 368 is provided with a small upstanding plate 372 (Fig. 8) which may be engaged by a slide rod 374 movable in a bore in a bracket of the machine frame and provided at its right-hand extremity with a fork-shaped member 376 (Fig. 9) embracing the screw shaft 206 part way to prevent rotation of the rod 374. Upon termination of a sawing operation the member 376 is engaged by the hub of the shell 200. Engagement of the shell 200 with the member 376 causes a displacement of that member and the rod 374 toward the left of Figs. 1 and 8, with the result that the hand lever 368 is rotated toward the left of Fig. 8 or in a clockwise direction to straighten or extend the toggle 362, 364 and to move the clutch member 346 out of engagement with the clutch member 344. The toggle 362, 364 being extended it acts as a locking means for holding the clutch disengaged against the pressure of the spring 350 which seeks to reestablish driving connection.

The feed controlling mechanism.—To facilitate the sawing operation, in particular to insure that the saw 60 does not bind when moving through its kerf, special mechanism is provided in connection with the previously mentioned cam shaft 52 for retarding or completely stopping the feed motion of the work temporarily and intermittently. In particular, the feed motion of the work is retarded or completely stopped during alternate strokes of the vertically reciprocating saw, and in the present instance the arrangement is such that the work feed is retarded or stopped during each upstroke of the saw or, in other words, that the work is fed or fed more rapidly during each downstroke of the saw. To accomplish this there is secured on the shaft 52 a cam block 380 (Fig. 7) provided with a peripheral groove, the center of the groove lying generally in a plane oblique to the axis of the shaft 52. The groove is engaged by a cam follower 382 which is rotatably mounted on a fixed bracket 384. As previously mentioned, the shaft 52 is mounted for sliding movement in the direction of its axis. As a result of the action of the stationary follower 382 on the cam block 380 the shaft 52 will be reciprocated axially during each revolution thereof. Upon displacement of the shaft 52 axially in one direction the worm 330 is so moved longitudinally with relation to the worm gear 332 meshing therewith that the motion of the worm gear 332 and of the entire mechanism rotated by it is retarded. If the throw of the cam 380 is equal to the lead of the worm 330, the motion of the worm gear 332 is completely stopped during the axial displacement of the shaft 52 in one direction. As may be seen best in Fig. 6, the ratio of transmission between the shafts 30 and 46, as well as that between the shafts 46

and 52, is one to one, thereby insuring that the variation of the feed movement of the work is in timed relation to the vertical reciprocation of the saw.

As illustrated in Figs. 1 and 6, the threaded shaft 64 of the saw support 62 is surrounded by a tray 390 which serves to catch the sawdust. The dust is removed by suction through a conduit 392 (Fig. 1).

The operation of the machine.—In the operation of the machine a wood block B of substantially cylindrical shape, which is to be divided into two nested components by a helical cut extending from one end face of the block to the other, is presented to the shell 200 and positioned therein in predetermined relation to the saw 60 by the manipulation of the hand wheels 260 and 304, whereupon the work-positioning and securing mechanism is locked to the shell 200 and the two shafts 206 and 208 integral therewith. It is understood that the shell 200 is located in its initial position illustrated in Fig. 1 from which it begins its work-feeding and rotating motion toward the left of that figure. The saw 60 extends through a slot 204 of the shell 208 and is positioned opposite one end face of the block B, as illustrated in Fig. 10.

Then the handle 368 is moved toward the right of Fig. 8 to establish driving connection between the clutch members 344, 346 and to rotate the nut 230. As a result the work-support 12, comprising the threaded shafts 206, 208 and the shell 200, is rotated and advanced along the axis of rotation, the extent of rotation and axial advance being controlled and determined by the nut 212 engaging the right-hand threaded shaft 208, as previously described. The work in thus being moved past the saw and rotated with relation to the saw is divided into two parts by a helically extending cut, as illustrated in Figs. 19 to 21. When the saw 60 emerges from the end face of the block B opposite to the end face where the sawing operation started, the hub of the shell 200 engages the fork 376 and pushes the hand lever 368 toward the left of Fig. 8 to throw out the clutch 344, 346 and terminate the sawing operation.

After the removal of the two divided work parts the shell 200 and the members connected therewith are then manually returned into initial position by means of the capstan 240, 242, the rotatable nut 230 spinning idly as well as the loosely rotating gear 342 meshing therewith.

Having described my invention what I claim as new and desire to secure by Letters Patent of the United States is:

1. In a woodworking machine, the combination of a rotary and longitudinally movable work support provided with two axially aligned screw shafts, a positively rotated nut engaging one of said screw shafts to rotate the work support, a stationary nut engaging the other screw shaft and controlling the extent of rotation and longitudinal movement of the work support, a saw for dividing the work into two nested components, and means for operating the saw.

2. In a woodworking machine, the combination of a rotary and longitudinally movable work support provided with two axially aligned screw shafts having different helix angles, a positively rotated nut engaging one of said screw shafts to rotate the work support, a stationary nut engaging the other screw shaft and controlling the extent of rotation and longitudinal movement of the work support, a saw for dividing the work into

two nested components, and means for operating the saw.

3. In a woodworking machine, the combination of a rotary and longitudinally movable work support provided with two axially aligned screw shafts having different helix angles, a positively rotated nut engaging the screw shaft having the larger helix angle to rotate the work, a stationary nut engaging the screw shaft having the smaller helix angle to control the extent of rotation and longitudinal movement of the work support, a saw for dividing the work into two nested components, and means for operating the saw.

4. In a woodworking machine, the combination of a rotary and longitudinally movable work support provided with two axially aligned screw shafts having oppositely extending threads, a positively rotated nut engaging one of said screw shafts to rotate the work support, a stationary nut engaging the other screw shaft and controlling the extent of rotation and longitudinal movement of the work support, a saw for dividing the work into two nested components, and means for operating the saw.

5. In a woodworking machine, the combination of a saw, a rotatable and longitudinally movable shell-like work support provided with slots and openings extending helically in the direction of the axis of rotation of the support to afford clearance for the saw in passing through the work when the latter is fed past the saw as a result of the longitudinal movement of the work support, two axially aligned oppositely threaded shafts rigid with the work support and arranged for rotation and longitudinal movement in the direction of their axis of rotation, means for operating the saw, means actuated by said saw operating means and engaging one of said shafts for rotating the shafts and the support, and means engaging the other shaft for controlling the extent of rotation and longitudinal movement of the shafts and the support.

6. In a woodworking machine, the combination of a saw, a rotatable and longitudinally movable shell-like work support provided with slots and openings extending helically in the direction of the axis of rotation of the support to afford clearance for the saw in passing through the work when the latter is fed past the saw as a result of the longitudinal movement of the work support, two axially aligned oppositely threaded shafts rigid with the work support and arranged for rotation and longitudinal movement in the direction of their axis of rotation, means for operating the saw, a positively rotated, axially immovable nut engaging one of said shafts and actuated by said saw operating means for rotating the shafts and the support, and a stationary nut engaging the other shaft for controlling the extent of rotation and longitudinal movement of both shafts.

7. In a woodworking machine, a vertically reciprocating saw, a movable work support arranged to feed the work past the saw, means for reciprocating the saw at a uniform rate of speed, support actuating means operated by said saw reciprocating means, a rotary and axially movable shaft included in said support actuating means, a worm on said shaft transmitting the rotation of the shaft to a worm gear included in said support actuating means, a cam on said shaft, and means cooperating with said cam for axially moving said shaft during the upstroke of the saw so as to move the worm bodily with

relation to the worm gear thereby reducing the feed movement of said support.

8. In a machine for dividing a last forepart block into two nested components corresponding roughly to two last foreparts, a saw, a hollow externally threaded shaft, a block support rigid with said shaft, means acting on the shaft to cause the support to rotate a block supported therein and longitudinally move it past the saw, aligned prongs for locating the block in a predetermined position with relation to the saw prior to a sawing operation, a screw operated sleeve arranged inside said shaft for relative movement thereto and carrying said prongs, means acting on said sleeve to maintain the prongs in alignment during said relative movement of the sleeve and the shaft, and means for locking said sleeve and shaft together after the completion of said relative movement.

9. In a woodworking machine, a work support, a saw having a blade twisted along its longitudinal axis, a support for said saw including a threaded member the helix angle of which corresponds to the helix angle of the twisted saw blade, means for reciprocating the saw support and a stationary member cooperating with the threaded member to rotate the saw support during the reciprocation thereof.
